UNITED STATES PATENT OFFICE.

JOSEPH FRIEDMAN, OF BROOKLYN, NEW YORK.

DESIGN FOR A KETTLE OR SIMILAR ARTICLE.

Application filed June 8, 1922. Serial No. 2,589. Term of patent 7 years.

To all whom it may concern:

Be it known that I, JOSEPH FRIEDMAN, a citizen of the United States, and a resident of the city of New York, in the borough of Brooklyn and State of New York, have invented a new, original and ornamental Design for a Kettle or Similar Article, of which the following is a specification, reference being had to the accompanying drawing, forming part thereof.

The figure is a perspective view of a Berlin kettle embodying my new design.

I claim:

The ornamental design for a kettle or similar article, as shown and described.

JOSEPH FRIEDMAN.
